DISPENSING APPARATUS

William Tamminga, Bronx, N. Y., assignor to
 Monitor Process Corporation, Jersey City, N. J.,
 a corporation of New Jersey

Application December 21, 1939, Serial No. 310,381

18 Claims. (Cl. 221—114)

This invention relates to the retail dispensing of milk and is directed more particularly to delivery can construction from which such milk may be dispensed and to the operating mechanism by which valvular means, associated with the can, may be manipulated to bring about the delivery of relatively small volumes of milk from the can in uniform, measured quantities.

Speaking generally, the invention comprises a milk delivery can provided at its bottom with a measuring chamber having inlet and outlet ports respectively controlled by tandem valves, made, according to this invention, from an integral elastic part adapted to be operated to close the inlet port and open the outlet port, and vice versa. These valves have a common tubular valve stem adapted to project upwardly through the body of the can and into a cylindrical passage formed in the neck thereof and the upper end of said valve stem is guided in said cylindrical passage. The passage is so formed as to be externally of the neck of the can and is adapted to be normally sealed by a disruptable seal through which an operating device, hereinafter more fully described, may be forced to disrupt the seal and be thereupon detachably secured to the valve stem for the purpose of actuating the tandem valves for the dispensing of the milk from the can.

The invention is directed to improvement of the operating devices for the valve stem and the means whereby these parts may be electrically operated.

The side wall of the can of this invention is preferably cut away below its bottom wall and novel means is provided for normally closing the resulting cut away portion and for covering and concealing the measuring receptacle of the can during shipment so as to maintain the same in a thoroughly sanitary condition and to preclude damage thereto during shipment.

Features of the invention, other than those adverted to, will be apparent from the herein-after detailed description and claims when read in conjunction with the accompanying drawings.

The accompanying drawings illustrate different practical embodiments of the invention, but the constructions therein shown are to be understood as illustrative, only, and not as defining the limits of the invention.

Figure 1 is a central vertical section through a can embodying the present invention with a portion of the can broken away.

Figure 1a is a section on the line 1a—1a of Figure 1.

Figure 2 is a fragmental plan view of the can shown in Figure 1 with various parts of the can cut away.

Figure 3 is an underneath plan view of the can of Figures 1 and 2.

Figure 4 is a section on the line 4—4 of Figure 3.

Figures 5, 6 and 7 are perspective views of different forms of closing and protecting members which may be employed.

Figure 8 is a perspective view showing a modified form of the invention.

Figure 9 is a view of a dispensing cabinet shown in section with the can therein and having mounted thereon operating devices for actuating the valve stem of the tandem valve, certain parts being shown in section and other parts in elevation.

Figure 10 is a section on the line 10—10 of Figure 9.

Figure 11 is a section of a modified form of the invention.

Referring to the drawings, 1 designates the body of a milk delivery can, 2 the neck thereof, and 3 the can bottom. A suitable cover 4 of conventional form has a substantially cylindrical skirt 5 adapted to fit into the neck to close the top of the can as is usual.

Embracing the lower portion of the can body 1 and extending appreciably below the bottom 3 thereof, is a skirt 6, reinforced at its bottom by an internal ring 7. The bottom 3 is provided adjacent the side wall of the body with an opening 8 and mounted on the exterior of the bottom, in registration with this opening, is a measuring receptacle 9, so associated with the opening as to form therein an internal bead 10 constituting a valve seat about the opening which serves as the inlet port of the measuring receptacle. This valve seat faces in a downward direction, as clearly appears from Figure 1. The measuring receptacle is secured to the bottom 3 by soldering, welding or in any other appropriate manner to provide a tight leak-proof joint between these parts and in such a way as to eliminate sharp corners in which extraneous and unsanitary matter might lodge. The bottom of the receptacle is provided with a central outlet port passage 11 formed within a depending neck

50 which is surrounded by a downwardly extending protecting flange 12. The upper end of the port passage 11 is formed with a valve seat 13 and with the valve seats 13 and 10 are adapted to cooperate tandem valves 14 and 15, respectively.

55 These two valves are formed integral with one

another on a valve member 16 which may be conveniently molded from rubber or other material of sufficient resiliency to insure liquid tight seals between the valves and their seats, as and when they are engaged with one another. I have found that a relatively soft molded rubber body is well adapted for this use.

The rubber valve body is provided in its top with an undercut socket 17 adapted to receive and frictionally grip the lower end of a hollow valve stem 18 which extends upwardly through the body of the can and projects through the wall of the breast of the can into a cylindrical guide 19 formed exteriorly of the neck and terminating at its upper end in an external bead 20, the upper edge of which is substantially in the same plane as the top bead of the can. The tubular guide 19 is positioned exteriorly of the neck with the side wall of the neck vertically channeled at 2a to receive therein a portion of the diameter of the guide, the cover 4 having a substantially cylindrical skirt 5 adapted to project into the neck of the can and complementarily channeled at 5a to register with the channel 2a in the neck. The guide 19 is of somewhat larger internal diameter than the external diameter of the valve stem and the latter is provided at its upper end with an internal bead 21 through which projects a rubber valve nipple 22. This rubber valve nipple has a relatively thick flange adapted to seat on the upper end of the valve stem and a depending tubular elastic sleeve 23 closes at its bottom by a relatively thickened portion which has therein a slit 24. Juxtaposed with the sides of the valve nipple are air vent openings 25, which, as shown in Figure 1, are normally spaced from the wall of the nipple, so that air can pass through an opening 26 in the lower valve member 16, thence upwardly through the hollow valve stem and exit through the vent openings 25 into the neck of the can and above the normal liquid level of the milk contained in the can.

The valve stem will of course be filled with milk up to the level of the milk in the can and to preclude uneven measurements of appreciable variation due to this fact, a filler rod 27 is preferably positioned within the tubular valve stem to substantially fill the same, but leave sufficient clearance within the valve stem to permit of the passage of air around the filler rod 27. The lower end of the rod 27 is swedged into a square shape, as indicated at 28, to form a head which centralizes the filler rod and precludes it from lifting in the valve stem when the valve member 16 is in place on the lower end thereof.

The upper end of the cylindrical guide 19 is closed during shipment of the full can of milk by a two ply seal, the inner ply 29 of which is of cardboard or relatively soft metal and is impervious, while the outer ply 30 is of a harder metal which, when wiped about the bead 20, will hold the inner ply in place. The outer ply, however, has a central opening 31 of a size substantially equal to the internal diameter of the guide, so as to permit access to the inner ply 29 and permit the same to be disrupted, as hereinafter explained.

The cover 4 of the can is provided, in alignment with the cylindrical guide 19, with an opening adapted to be normally closed by a seal 32 which is preferably of metal and may be disrupted and removed. Registration between the openings in the cover and guide may be insured by a positioning slot 33 formed in the skirt 5 of

the cover and cooperating with a pin 34 mounted on the interior of the neck.

It will be understood that milk is dispensed from the can of this invention by inserting an appropriate implement or valve operating device through the opening in the top of the can and into the upper end of the guide 19, after the seals associated therewith have been removed or broken, as will be presently explained, and by manipulating such implement to longitudinally move the valve member 16 to seal or unseal the outlet port 13. The milk flows through the outlet port passage 11 into any appropriate receptacle positioned below the same.

To facilitate access to the discharge port passage, the skirt 6 of the can is preferably cut away in juxtaposition with the measuring receptacle, as shown at 35. In the construction of Figures 1, 2, 3, 4 and 9, the skirt is cut away from a point just below the bottom 3 to the bottom of the skirt, whereas in the structure of Figure 8, the skirt is cut away as shown at 35a in a manner to terminate at the upper edge of the reinforcing ring 7, so that the cut away portion 35a is a four-sided opening. In either event, it is desirable to properly reinforce the bottom of the skirt and this is accomplished by welding into place parallel reinforcing bars 36 with a transverse reinforcing bar 37. These bars 36 and 37 are of sufficient thickness and depth to furnish the reinforce desired and to thus strengthen the skirt.

With a can, constructed as described, the measuring receptacle projects below the bottom 3 of the can and it is desirable during shipment to cover and conceal the same, so as to protect it from damage and at the same time keep it clean and sanitary. The outlet port passage 11 is covered during shipment of the can by a removable seal 38 which is pressed into the annular flange 12 in a manner to be stressed into facial contact with the outer end of the passage 11, and the measuring chamber is, additionally, adapted to be covered by a removable protective housing 39 adapted to closely fit thereover and be secured in place against inadvertent displacement. This housing may be formed in various ways and it may be held in position by any suitable holding device. As shown in Figures 1-4, the housing is in the form of an inverted cup adapted to be slipped over the measuring receptacle from the bottom and this cup has a lateral extension 40 shaped to conform to the contour of the skirt and to form a continuation thereof at the cut away portion 35 of the latter. Offset keepers 41 are attached to the extension and are adapted to cooperate with the extension to form guide slots 42 which, when the protecting cup is slipped into place, will engage with the opposite upright margins of the cut away portion 35 and thus align the extension with the skirt wall, while the cup completely covers the measuring receptacle.

One of the reinforcing bars 36 (see Figures 3 and 4) is provided with a lateral extending ear 43 to which is pivoted, at 44, a spring arm 45 adapted to swing about this pivot and bowed, as shown at 46, so that, when this arm is brought into position to underlie the protecting cup 39 with the end of the arm forced beneath the other reinforcing bar 36, as shown in full lines in Figures 3 and 4, the arm will be under sufficient tension to hold the protecting cup in place. If the arm, however, is moved from the full line of position of Figure 3 in a counterclockwise direction and its end tucked beneath the diagonal brace 37, the cup will be released, while the arm will be

frictionally and resiliently held in this retracted position. The cup may then be removed carrying with it the extension 40, so that access may be had to the seal 38 which can then be removed to allow the milk to be dispensed.

The protective cup and extension 40 may, if desired, be formed in other ways than shown. Figure 6, for example, shows a modified form of the same construction and Figure 7 shows another modified form, but, in the latter figure, the cut away portion 35 of the skirt is not closed or filled in by an arcuate wall as in the previous figures. The projecting angular flanges 47 in Figure 7 merely rest against the margins of the cut away portion 35 and act as reinforcing struts for said margins to preclude their bending if the can is set down forcibly in such manner that a skirt will strike the floor in the vicinity of the cut out.

Figure 8 shows very clearly the manner in which the bowed spring arm 38 serves to lock the protecting cup in position and in this figure the cup of Figure 7 is shown in place.

Figure 1 shows the positions of the parts when the can is filled with milk and shipped to the retail dealer. The cover of the can has an associated seal 32 above the cylindrical guide of the valve stem and said guide is likewise sealed by the two ply seal 38, while the seal 38 covers the outlet port passage 41. The protecting cup is in place and locked in this position by the spring arm 45.

When such a can is delivered to the retailer and he prepares to set the structure into position to dispense milk, the first operation in this connection consists in moving the spring arm 45 from the dotted line position of Figure 2 to the dot and dash line position, i. e., from the full line position of Figure 3 to the dot and dash line position thereof. By so doing the protecting cup 39 is released and may be withdrawn through the lower end of the skirt leaving the measuring receptacle exposed and the cut out 35 of the skirt unencumbered. The seal 38 at the bottom of the measuring receptacle is then removed. The seal 32 of the cover is next removed and the dealer thereupon breaks the seal 29 above the valve stem, and connects to the latter a valve operating device, embodying the structure and operating in the manner next to be described.

The valve operating device is shown in Figures 9 and 10. It comprises a tubular sleeve 48 having a reduced lower end extension 49 of cylindrical form preferably terminating in a sharp edge. In this reduced part a plurality of balls 50, similar to ball bearings, are positioned in holes in the walls of said extension, and these holes are countersunk on the inside, so as to let the balls seat in the holes without falling outwardly therethrough.

Extending downwardly through the sleeve 48 is a tubular shank 51, the lower end of which is tapered, and this shank is provided above the top of the sleeve 48 with a head 52 which, when forced downwardly, will spread the balls 50. Between the head 52 and the sleeve 48 is a rubber gasket 53 and the faces of these parts adjacent the gasket are complementarily ridged and channeled, so that, when the head is forced down tightly on the sleeve, a tight joint will be assured between these parts.

Relative movement between the sleeve and head is imparted by a finger piece 54 of substantially U-shaped cross section and it straddles the sleeve 48 and is pivoted to the opposite sides 75

thereof by alined pivots 55. The two legs of the U-shaped finger piece 54 are of substantially bell crank form and they are provided at their elbows with pivots 56, secured to links 57, which are in turn secured to the head 52, so that, when the finger piece is swung downwardly, as indicated by the arrow in Figure 9, the head will be forced downwardly to a firm seat on the sleeve and simultaneously the lower tapered end of the shank 51 will engage with the balls and force them outwardly.

In associating a device of this kind with the can, the seal 32 of the cover opening 32a is first removed and the sleeve thereupon forcibly projected downwardly through the opening 32a upon the top of the seal 30. As a result, the lower end of the sleeve 48 will pass through the opening 31 in the outer ply of this seal and said lower end will disrupt and break away the central portion of the inner ply 28, to the extent necessary to permit the sleeve to pass downwardly therethrough, as shown in Figure 9. The reduced lower end of the sleeve will thereupon enter into the rubber nipple in the upper end of the valve stem, until the shoulder at the base of the reduced portion 49 seats upon the thickened flange of the nipple 29. This brings the parts to rest with the sleeve resting on the top of the nipple, as shown in Figure 9. If the finger piece 54 is thereupon swung downwardly, as indicated by the arrow in Figure 9, the shank 51 will act upon the balls 50 to force them in an outward radial direction and distend the wall of the nipple directly beneath the internal bead 21 of the tubular valve stem, with the result that the sleeve 48 will be locked to the valve stem and will remain locked thereby so long as the finger piece is in its lowermost position for in this position the links 57 will have passed beyond dead center. With the sleeve 48 and head 52 thus locked to the valve stem, it will be apparent that movement of these parts will effect movement of the tandem valves and thus bring about dispensing of milk from the can in measured quantities, appropriate to the volume of the measuring receptacle.

I consider it quite important to have the sleeve 48 break away the seal 30 in the manner shown, rather than to actually remove the seal, for so long as this seal is in place, a dealer is not free to reach in through the top of the guide 19 and remove the rubber nipple 29. If we were able to do so, it would be possible to introduce foreign material, such as water, into the can, and in the absence of the ability to remove the nipple, such a practice would not be feasible.

After the sleeve and head of the valve operating device have been associated with the can, the can may be set into a suitable dispensing cabinet 59, which is preferably refrigerated to keep the milk cool. With this cabinet is associated means to engage with and operate the head for the purpose of vertically receiving the valve stem. This means is shown as embodying a fitting comprising a cylindrical body 60 provided at its lower end with an undercut seat in which is positioned an elastic gasket 61 adapted to rest on the top of the head 52 which is recessed to receive therein a strainer 62. Embracing the cylindrical body 60 is a sleeve 63 provided at its bottom with an in-turned flange 64 and substantially one-half of the lower portion of this sleeve is cut away, so that the sleeve may be lowered off-center of the head 52 until the flange 64 is opposite the peripheral channel 65 in the head 52 and if the sleeve is thereupon moved into axial alignment with the

head the flange 64 will thereupon enter into the channel 65. The sleeve is also provided at its opposite sides with openings 66 shown best in Figure 10 and in these openings are positioned eccentricities 67 mounted on pins 68 which extend into alined perforations in the opposite sides of the body 60. A bifurcated finger piece 69 is made rigid with the eccentricities 67 and when this finger piece is moved into the position shown in Figure 10, it will shift the eccentricities to clamp the gasket 61 firmly between the lower end of the body 60 and the upper end of the head 52 and firmly hold the flange 64 in engagement with the annular channel 65 in said head to thereby lock these parts together, whereby reciprocation of the cylindrical body 60 will impart a like movement to the head and connected valve stem.

The upper end of the head is shown as secured to the lower end of a coil spring 70 which extends upwardly through an opening in the top of the cabinet and is secured at its upper end to a lever 71. This lever is of the second class, is fulcrumed at 72 to a bracket on the top of the cabinet, and is secured, at its free end, to a link 73 connected to the core of a solenoid 74. The spring 70 tends to normally assume a neutral position, but when the solenoid is energized to lift the outboard end of the lever 71, a resilient pull will be exerted through the spring upon the valve operating device to lift the valve stem. When the solenoid is de-energized, its core will descend and put a pressure upon the spring to assist gravity in lowering the valve stem. Thus, by controlling the energizing of the solenoid in any suitable way as by coin controlled means or otherwise, the operations of the valves in the dispensing of measured quantities of milk can be accurately controlled.

For example: under normal conditions, the parts will appear as in Figure 9. The outlet valve 14 will be closed while the inlet valve 15 will be opened, so that milk may flow from the interior of the can into the measuring receptacle to fill the same. During the flow of milk into the measuring receptacle, air which may be displaced is free to escape through the vent opening 26 in the valve member 16 and flow upwardly through the valve stem and out through the vent openings 25 into the upper portion of the can above the milk level therein. If the solenoid is thereafter energized the valve stem will be lifted to unseat the outlet valve 14 and seal the inlet valve 15. This will preclude the flow of milk from the body of the can into the measuring receptacle, but will allow the flow of milk from the measuring receptacle through the outlet port passage 11 into a receptacle, such as a tumbler, positioned beneath the same. During this operation, the building up of a vacuum which would interfere with the proper flow of milk is precluded by the passage of air in a retrograde direction through the valve stem to take the place of the liquid drawn from the measuring receptacle. By thus permitting the flow of air in both directions, a more smooth and steady flow of milk is obtained than could otherwise be accomplished.

It is desirable in the retail dispensing of milk to provide some appropriate means for agitating the milk in the can for, in the absence of such provision, the milk will tend to stratify, with the cream in the upper layer and consequently an equitable distribution of the cream in each dispensed quantity will not be had. I prefer to effect agitation of the milk in accordance with this invention by introducing air under pressure into the milk through the measuring chamber and this

air is introduced into the measuring chamber by passing it downwardly through the valve operating devices and through the valve stem. To this end, air under pressure is supplied from any suitable source through a tube 76 leading to a passage 77 extending axially through the cylindrical body 60 to the gasket 61 which is centrally perforated. The air thus fed passes through the screen 62 and is fed through a central passage 78 extending downwardly through the head 52 and the shank 51 to about half way down the length of the latter where it exits into the interior of the sleeve 48. It passes downwardly through the interior of the sleeve and around the lower end of the shank 51 into the interior of the rubber nipple 20 and its pressure is sufficient to expand the thin tubular side walls of the rubber nipple sufficiently to close the vent openings 25 and to force the slit 24 (Figure 1) at the bottom of the nipple open. In this way the compressed air enters into the tubular valve stem 18, passes downwardly therethrough and exits through the vent opening 26 into the measuring chamber, from whence it bubbles upwardly through the opening 8 into the body of the can, and, rising through the milk in the form of bubbles, serves to thoroughly agitate the milk in the can body and assure an equitable distribution of cream therein at all times. The air may be supplied periodically and at stated intervals of sufficient duration to produce the agitation desired.

When the contents of the can have been fully dispensed, the can is disconnected from its valve operating devices and from the cabinet in the following manner. The finger piece 69 is first pressed down. This unlocks the fitting from the head 52 and said fitting may be moved rearwardly to disengage said head. The can may then be removed from the cabinet and the finger piece 54 lifted. This operation will retract the tapered lower end of the shank 51 from the balls 50 and the resiliency of the rubber nipple 20 will force these balls inwardly to disengage the sleeve from the bead 21. The sleeve 48, together with the shank 51, may then be lifted out of the upper end of the valve stem and free from the guide 18, leaving the can wholly unobstructed. The protective cup 39 may then be applied and locked in place by the spring arm 45 and the can is thereupon ready to be returned to the creamery. Upon arrival the parts may be readily dismantled in a manner which will be clear to those skilled in the art and may be thoroughly cleaned, assembled, sterilized and the can refilled with milk and the cover attached for shipment.

All of the parts of the can and the dispensing mechanism which is directly associated therewith may be easily and thoroughly dismantled and the rubber parts in particular may be removed and replaced at will by creamery employees. There are no sharp corners to collect dirt or foreign matter and every part of the structure is susceptible to the most thorough cleansing without undue labor.

Figure 11 shows a modified form of the construction shown in Figure 9 and more particularly that portion of the valve operating device which couples directly to the valve stem 18. In the construction of Figure 11 the upper end of the valve stem has mounted thereon by welding or otherwise a cage-like fitting 80 provided with an inturned flange 81 and the lower end of the sleeve 40 is provided with a ridge 82 which seats directly on the top flange of the valve nipple 20,

so that said sleeve is not provided with a reduced extension as in Figure 9. The clutch balls 50 are mounted in countersunk holes in the lower end of the sleeve and are operated on by the shank 51 which may be of a larger diameter than the shank 51 in Figure 9, but acts upon the balls in the same way to force them outwardly when the shank is lowered, so that said balls engage with the under side of the flange 81 of the cage 80 and lock the valve stem to the sleeve 48. With this arrangement no internal bead, corresponding to the bead 21 of Figure 9, is necessary at the upper end of the valve stem and consequently the interior of the valve stem is not constricted and thus may be more easily cleaned than in the construction of Figure 9. Likewise the upper end of the tubular guide 19 is shown as free from an external bead and the seal 30, indicated in dotted lines, may be of the ordinary friction type.

It will also be noted that in Figure 11, the vent holes 82 which correspond to the face 25 in Figure 9 are provided with internal lips, so as to normally contact directly with the thin wall of the nipple valve 20. This wall is sufficiently flexible to yield when sub-atmospheric pressures are present within the tubular valve stem, so as to permit air to pass into the valve stem through said vents. When pressure is built up within the valve stem and externally of the rubber nipple, the nipple will be collapsed sufficiently to unseal the vents, so that such pressure may be relieved therethrough. However, when compressed air is admitted into the nipple for agitation as hereinbefore described the air vents 82 be effectually sealed, so that such compressed air cannot be discharged through these vents but must pass downwardly to the measuring receptacle from whence it enters into the can to bubble up through the milk and carry out the agitation described.

The foregoing detailed description sets forth the invention in its preferred practical form and the invention is to be understood as fully commensurate with the appended claims.

Having thus fully described the invention, what I claim as new and desire to secure by Letters Patent is:

1. In an assembly of the character described, a milk can comprising a body, the upper portion of which is contracted to form the breast of the can and on which breast is superimposed a can neck, a tubular guide positioned exteriorly of the neck and extending from the breast to substantially the top of the neck and open to the interior of the can, there being an opening provided in the bottom of the can below said guide, a valve cooperating with said opening and having a valve stem extending upwardly through the body of the can and projecting into the guide, a disruptable seal for normally closing the upper end of the tubular guide, and a can cover adapted to close the top of the can and projecting exteriorly of the neck in a lateral direction sufficiently to overlie the upper end of the guide, said cover having therein an opening juxtaposed with the guide and through which access may be had to said disruptable seal.

2. In an assembly of the character described, a milk can comprising a body, the upper portion of which is contracted to form the breast of the can and on which breast is superimposed a can neck, a tubular guide positioned exteriorly of the neck and extending from the breast to substantially the top of the neck and open to the

interior of the can, there being an opening provided in the bottom of the can below said guide, a valve cooperating with said opening and having a valve stem extending upwardly through the body of the can and projecting into the guide, a disruptable seal for normally closing the upper end of the tubular guide, a can cover adapted to close the top of the can and projecting exteriorly of the neck in a lateral direction sufficiently to overlie the upper end of the guide, said cover having therein an opening juxtaposed with the guide and through which access may be had to said disruptable seal, and an additional disruptable seal normally closing said opening in the cover.

3. In an assembly of the character described, a milk can comprising a body, the upper portion of which is contracted to form the breast of the can and on which breast is superimposed a can neck, a tubular guide positioned exteriorly of the neck with the side wall of the neck vertically channeled to receive therein a portion of the diameter of the guide, a cover having a substantially cylindrical skirt adapted to project into the neck of the can and complementarily channeled to register with the channel in the neck, said cover having a laterally extending flange projecting to overlie the upper end of the tubular guide and having in said flange an opening registering with said guide, there being provided in the bottom of the can an outlet opening, and a valve cooperating with said opening in the bottom of the can and having a valve stem extending upwardly through the body of the can and through the breast thereof and guided for vertical reciprocation in the tubular guide.

4. In an assembly of the character described, a milk can comprising a body, the upper portion of which is contracted to form the breast of the can and on which breast is superimposed a can neck, a tubular guide positioned exteriorly of the neck and extending from the breast to substantially the top of the neck and open to the interior of the can, there being an opening provided in the bottom of the can below said guide, a valve cooperating with said opening and having a valve stem projecting upwardly through the can body and guided for vertical reciprocation in the tubular guide and provided at its upper end with a clutch member and a valve operating member projecting into the guide from the upper end thereof and also having a clutch member to engage with the clutch member of the valve stem for the purpose of securing the latter to the valve operating member.

5. In an assembly of the character described, a milk can comprising a body, the upper portion of which is contracted to form the breast of the can and on which breast is superimposed a can neck, a tubular guide positioned exteriorly of the neck and extending from the breast to substantially the top of the neck and open to the interior of the can, there being an opening provided in the bottom of the can below said guide, a valve cooperating with said opening and having a valve stem projecting upwardly through the can body and guided for vertical reciprocation in the tubular guide and provided at its upper end with an internal bead, a tubular valve operating member projecting downwardly into the tubular guide and into the upper end of the valve stem and carrying a series of relatively extensible gripping members, and a gripping member operating element extending downwardly through the tubular valve operating member to force the gripping members

into engagement with the bead of the valve stem to lock said tubular operating member to the valve stem.

6. In an assembly of the character described, a can comprising a body having at its bottom a measuring receptacle provided with an inlet orifice through which milk may flow from the can into the measuring receptacle and an outlet orifice through which milk may be discharged from the measuring receptacle, valvular means cooperating with the orifices to close one and open the other as desired, a protective cup positioned exteriorly of the can and adapted to house and conceal the measuring receptacle when the can is conditioned for shipment, and means for securing the protective cup in receptacle housing position, the body of the can being provided with a depending skirt extending downwardly from the bottom of the can to a plane below the bottom of the protective cup, and which skirt has an opening juxtaposed with the cup, said cup being formed to close the opening in the skirt when the cup is in a position to house the measuring receptacle.

7. A valve operating device comprising a tubular sleeve having a depending reduced extension with perforations therein and balls seated in said perforations, a head above the sleeve having a shank extending downwardly through the sleeve and into the reduced extension thereof and there provided with a tapering end portion to coat with said balls, a bell crank mounted on the sleeve with its elbow linked to the head and adapted through pivotal movement to impart axial movement between the shank and the sleeve, said head being provided with a circumferential channel, a tubular member adapted to rest on the head, eccentrics pivoted to said tubular member, a finger piece rigid with said eccentrics, a sleeve embracing the tubular member with cut outs therein for cooperation with the eccentrics and having an internal cut away flange to engage with the channel of the head and adapted to clamp the head to the tubular member when the finger piece is operated to force the eccentrics to draw the head into engagement with the cylindrical member, and means connected with the cylindrical member to axially reciprocate the same.

8. A valve operating device comprising a tubular sleeve having a depending reduced extension with perforations therein and balls seated in said perforations, a head above the sleeve having a shank extending downwardly through the sleeve and into the reduced extension thereof and there provided with a tapering end portion to coat with said balls, a bell crank mounted on the sleeve with its elbow linked to the head and adapted through pivotal movement to impart axial movement between the shank and the sleeve, said head being provided with a circumferential channel, a tubular member adapted to rest on the head, eccentrics pivoted to said tubular member, a finger piece rigid with said eccentrics, a sleeve embracing the tubular member with cut outs therein for cooperation with the eccentrics and having an internal cut away flange to engage with the channel of the head and adapted to clamp the head to the tubular member when the finger piece is operated to force the eccentrics to draw the head into engagement with the cylindrical member, means connected with the cylindrical member to axially reciprocate the same, there being an air passage extending through the cylindrical member, head, shank and the sleeve

which surrounds the latter to permit the passage of air under pressure therethrough.

9. In an assembly of the character described, a tubular valve stem provided at its free end with an undercut cage having therein a gasket, a sleeve adapted to project into the cage and bear upon the gasket and carrying a plurality of balls normally retracted to permit the sleeve to be introduced into the undercut portion and removed from said portion of the cage, and a shank within the sleeve and having a tapered end for forcing the balls in an outward radial direction into the undercut portion of the cage for the purpose of locking the sleeve firmly to the valve stem and forcing said sleeve to a firm seat on said gasket.

10. In an assembly of the character described, a can comprising a body having a side wall and a bottom wall, a measuring receptacle positioned below said bottom wall and provided with an inlet orifice through which milk may flow from the can into the measuring receptacle, an outlet orifice through which milk may be discharged from the measuring receptacle, valvular means cooperating with the orifices to close one and open the other as desired, a protective cup positioned below said bottom wall exteriorly of the can and adapted to house and conceal the measuring receptacle when the can is conditioned for shipment, means for securing the protective cup in receptacle housing position, said side wall having a depending skirt extending downwardly from the bottom wall of the can to a plane below the bottom of the protective cup and enclosing said cup on all lateral sides.

11. In an assembly of the character described, a can comprising a body having a side wall and a bottom wall, a measuring receptacle positioned below said bottom wall and provided with an inlet orifice through which milk may flow from the can into the measuring receptacle, an outlet orifice through which milk may be discharged from the measuring receptacle, valvular means cooperating with the orifices to close one and open the other as desired, a protective cup positioned below said bottom wall exteriorly of the can and adapted to house and conceal the measuring receptacle when the can is conditioned for shipment, means for securing the protective cup in receptacle housing position, said side wall having a depending skirt extending downwardly from the bottom wall of the can to a plane below the bottom of the protective cup and enclosing said cup on all lateral sides, said skirt having an opening at one side juxtaposed with the cup.

12. A liquid dispensing device comprising a tube provided with an open end adjacent which the wall of the tube has a vent opening surrounded by an inwardly projecting nozzle extending from the wall of the tube and the inner end of which forms a valve seat, an elastic valve nipple extending into the open end of the tube and having a tubular cylindrical body, the wall of which is of such exterior diameter as to normally at least substantially contact with the valve seat of said nozzle, said tubular body being open at its outer end and closed at its inner end, the inner end having a thickened wall provided therein with a slit normally closed and the cylindrical wall of the body being sufficiently thin and elastic to form an air-tight seal with said valve seat and close the vent opening therein when sufficient air pressure is introduced into the tubular body to open the slit in the end of the tube and to collapse and unseal said vent opening when

pressure in the tube exceeds the pressure in the valve nipple.

13. A liquid dispensing device comprising a tube provided with an open end adjacent which the wall of the tube has vent openings therein, each of which is surrounded by an inwardly projecting nozzle extending from the wall of the tube and the inner end of which forms a valve seat, an elastic nipple valve extending into the open end of the tube and having an elastic collapsible tubular cylindrical body open at its outer end and closed at its inner end with the inner end having a normally closed pressure outlet, the normal diameter of the cylindrical body of the nipple valve being such as to engage with the valve seats of the vent openings.

14. A liquid dispensing device comprising a tube provided with an open end adjacent which the wall of the tube has a vent opening therein surrounded by an inwardly projecting nozzle extending from the wall of the tube and the inner end of which forms a valve seat, an elastic nipple valve extending into the open end of the tube and having an elastic collapsible tubular cylindrical body open at its outer end and closed at 25 its inner end with the inner end having a normally closed pressure outlet, the diameter of the cylindrical body of the nipple valve being such as to engage with the valve seat of the vent opening when pressure is admitted into the valve nipple.

15. In an assembly of the character described, a milk can comprising a body, the upper portion of which is contracted to form the breast of the can and on which breast is superimposed a can neck, a tubular guide positioned exteriorly of the neck and extending from the breast to substantially the top of the neck and open to the interior of the can, there being an opening provided in the bottom of the can below said guide, a valve cooperating with said opening and having a 40 valve stem extending upwardly through the body of the can and projecting into the guide, and a can cover adapted to close the top of the can and projecting exteriorly of the neck in a lateral direction sufficiently to overlie the upper end of the guide.

16. In an assembly of the character described, a milk can having an upright tubular guide at

its top and an opening in the bottom of the can below said guide, a valve cooperating with said opening and having a valve stem projecting upwardly through the can and guided for vertical sliding reciprocation in the tubular guide to open and close the valve and provided at its upper end with a clutch member, and a valve operating member projecting into the guide from the upper end thereof and also having a clutch member to engage with the clutch member of the valve stem for the purpose of securing the latter to the valve operating member against relative axial movement.

17. In an assembly of the character described, a milk can having an upright tubular guide at its top and an opening in the bottom of the can below said guide, a valve cooperating with said opening and having a valve stem projecting upwardly through the can and guided for vertical reciprocation in the tubular guide and provided at its upper end with an internal bead, a tubular valve operating member projecting downwardly into the tubular guide and into the upper end of the valve stem and carrying a series of relatively extensible gripping members, and a gripping member operating element extending downwardly through the tubular valve operating member to force the gripping members into engagement with the bead of the valve stem to lock 30 said tubular operating member to the valve stem.

18. In an assembly of the character described, a milk can having an upright tubular guide at its top and an opening in the bottom of the can below said guide, a valve cooperating with said opening and having a valve stem projecting upwardly through the can and guided for vertical sliding reciprocation in the tubular guide to open and close the valve and provided at its upper end with a clutch member, a valve operating member projecting into the guide from the upper end thereof and also having a clutch member to engage with the clutch member of the valve stem for the purpose of securing the latter to the valve operating member against relative axial movement, and electrically operable means connected to said valve operating member to axially reciprocate the same.

WILLIAM TAMMINGA.
